R. HUGHES.
BAYONET CLUTCH.
APPLICATION FILED DEC. 22, 1917.

Patented Nov. 19, 1918.

Rufus Hughes Inventor
By his Attorney
James B. Jackson, Esq.

UNITED STATES PATENT OFFICE.

RUPERT HUGHES, OF NEW YORK, N. Y.

BAYONET-CLUTCH.

1,285,189.

Specification of Letters Patent. Patented Nov. 19, 1918.

Application filed December 22, 1917. Serial No. 208,399.

To all whom it may concern:

Be it known that I, RUPERT HUGHES, a citizen of the United States of America, and a resident of the city, county, and State of 5 New York, have invented an Improvement in Bayonet-Clutches, of which the following is a specification.

This invention relates generally to weapons and particularly to the class of weapons 10 including bayonet equipped rifles, or the like.

The principal object of the invention is to provide a device, herein shown as an attachment, by which an opponent's weapon 15 can be caught, his blow parried or his weapon wrenched from his grasp.

A preferred embodiment of the invention has been selected for purposes of illustration, and is herein shown as an attachment 20 to be applied to a rifle near the muzzle for use in bayonet fighting. The accompanying drawings show an illustrative embodiment of the invention, and therein

Figure 1 shows the device attached to a 25 rifle of a standard type;

Fig. 2 is an enlarged view of the device;

Fig. 3 is a side elevation, and

Fig. 4 is a section on the line 4—4 of 30 Fig. 3.

Referring to the drawings a rifle 10 of the usual construction is shown. A bayonet 11 is affixed to the rifle in the usual way. Near the muzzle of the rifle the attachment 12, which may be termed a "bayonet clutch" 35 is fastened by metal straps 13 and 14. The bayonet clutch comprises a substantially U-shaped member having an inner arm 15 securely fastened to the straps 13 and 14 by any suitable means such as rivets 16. The outer arm 17 is bent back along the line of 40 the lower arm thus forming a hook, which, when the device is attached as shown in Fig. 1, opens toward the muzzle of the rifle.

A latch member 18 is provided to close 45 the open end of the hook and it is preferably pivoted at 19 to the arm 15. This latch is held in position to close the opening by a spring 20 coiled about the pivot pin 21. The arm 15 of the clutch is slotted so that 50 the catch lever 18 may be pressed downwardly to allow an opponent's weapon sliding along the rifle to pass into the hook. Thereafter the spring will raise the catch lever 18 to the position shown, thus preventing 55 the withdrawal from the hook of an opponent's weapon by movement longitudi-

nally of the rifle shown, or in fact by movement in any direction except that perpendicular to the plane of the clutch.

The bayonet clutch may be attached to 60 the rifle by any suitable means, preferably by the metal straps 13 and 14, before referred to. These straps may be tightened upon the stock of the rifle by set screws 22 and 23. The construction of these screws 65 may be identical and a description of one will suffice for the other. The straps are provided with bosses 24 and 25 preferably formed integral therewith. The set screws run freely through the bosses 24 and are 70 threaded in the bosses 25. The screws are provided with cross-pins 26 for use in tightening the screws and the ends of the screws may be peened over so that they cannot be entirely withdrawn from the bosses 25. 75

The lower strap 13 may be provided with an upturned lip 27 for the protection of the thumb of the user as the rifle stock is grasped just below the strap.

The particular embodiment of the invention herein shown is intended to be used in bayonet fighting and a sufficient description of its intended operation will be given to show the application and utility of the invention, although other methods of use 85 may be developed in practice.

It will be noted that the bayonet clutch is preferably mounted upon the left hand side of the rifle; that being the side generally used in parrying an opponent's 90 thrust. When parrying a blow or thrust by an opponent the user's bayonet may be crossed with his opponent's bayonet which may strike upon the left hand side, and if the opponent's bayonet strikes between the 95 clutch and the end of the user's bayonet the user may so manipulate his rifle as to cause his opponent's bayonet to slide toward him along his own bayonet and it may enter the bayonet clutch and be arrested at the closed 100 end of the hook. Thereupon the catch arm 18 will spring back into place and prevent any further movement of the opponent's bayonet along the barrel or away from it except in a direction substantially at right 105 angles to the plane of the clutch member. The angular movement of the crossed weapons will also be limited. By a quick twist or turn, or a depression or elevation of the muzzle of the user's rifle his opponent's bayonet, being firmly held within the clutch, may be broken or his weapon 110

- wrenched from his grasp. In any event the bayonet clutch will make it possible to get a hold upon an opponent's weapon which can be availed of to considerable advantage.
- 5 In case of an attack upon the side of the weapon unprovided with a clutch the clutch may be brought into action and engagement with the opponent's weapon by a simple rotation of the weapon through 180 degrees.
- 10 It will be understood that the invention may be variously modified and embodied within the scope of the subjoined claims.
- I claim as my invention:
1. A rifle provided with a bayonet and having mounted upon its stock adjoining the hilt of the bayonet a hook shaped member opening toward the muzzle of the rifle, and means for closing said opening, said hook shaped member and closing means acting to permit seizure of an opponent's weapon and to prevent withdrawal therefrom except longitudinally thereof and transversely of said rifle.
  2. A weapon of the character described having an offset member adjacent its forward end forming an opening toward the point of the weapon, and means for closing said opening and for permitting entrance to such member from the point of the weapon, said offset member and closing means acting to permit seizure of an opponent's weapon and to prevent withdrawal therefrom except longitudinally thereof and transversely of said first mentioned weapon.
  3. A weapon of the character described having an offset member adjacent its forward end forming an opening toward the point of the weapon, and means adapted to close said opening permitting entrance to

said member from the point of the weapon and preventing egress therefrom in a reverse direction.

4. A weapon of the character described having a hook shaped guard opening toward the point of the weapon and a spring pressed latch normally closing the open end of said guard.

5. A rifle provided with a bayonet and having mounted upon its stock adjacent the hilt of the bayonet a hook shaped member opening toward the muzzle of the rifle, and a spring latch normally closing the opening in said hook shaped member.

6. An attachment for rifles provided with a bayonet comprising a substantially hook shaped member having a catch lever pivoted to one arm thereof and attaching devices adapted to be passed around the stock of the rifle to fix the attachment thereon.

7. An attachment for rifles provided with a bayonet comprising a substantially hook shaped member having a catch lever pivoted to one arm thereof, attaching devices adapted to be passed around the stock of the rifle to fix the attachment thereon, and a lip upon one of said attaching devices to form a guard.

8. A device adapted to be attached to a weapon of the class described, said device having an entrance portion opening toward the point of the weapon and permitting the entrance of another weapon therein from the direction of the point of the weapon to which the device is attached, and means to prevent the egress thereof in said direction.

In testimony whereof I have signed my name to this specification this nineteenth day of December, 1917.

RUPERT HUGHES.
